CLAIM

The ornamental design for the joint ledger with tab, as shown and described.

DESCRIPTION

FIG. 1 is a front plan view of a joist ledger with tab showing my new design in the preferred embodiment.

FIG. 2 is a top plan view of the joist ledger with tab.

FIG. 3 is a bottom plan view of the joist ledger with tab.

FIG. 4 is a right side plan view of the joist ledger with tab.

FIG. 5 is a left side plan view of the joist ledger with tab.

FIG. 6 is a rear plan view of the joist ledger with tab.

FIG. 7 is an enlarged fragmented, elevational view of what is shown in FIG. 1;

FIG. 8 is an enlarged right side elevational view;

FIG. 9 is a top perspective view of the joist ledger with tab.

FIG. 10 is a right side plan view of an alternate embodiment of the invention having holes in the tab; and,

FIG. 11 is a left side plan view of the alternate embodiment shown in FIG. 10.

The undisclosed views of the second embodiment are identical in appearance to those shown for the first embodiment.
